ATTORNEY

UNITED STATES PATENT OFFICE.

JOHN F. ALEXANDER, OF NEW YORK, N. Y.

HOLLOW AUGER.

1,231,551.

Specification of Letters Patent.

Patented July 3, 1917.

Application filed January 11, 1916. Serial No. 71,512.

To all whom it may concern:

Be it known that I, JOHN F. ALEXANDER, a citizen of the United States, and a resident of the city of New York, in the county and State of New York, have invented certain new and useful Improvements in Hollow Augers, of which the following is a specification.

The present invention relates to improvements in hollow augers, and particularly such an auger for making holes in plaster wall whether ceiling or side, for the reception of electric outlet boxes, and fixture connecting devices. An object of the invention is to provide such a device which may be operated in a quick and efficient manner and will make a clean cut and properly positioned opening about a given center. Another object is to provide a device of this character which will be entirely self contained and will receive and retain all material cut from the ceiling or side wall thereof, enabling such work to be done without dirt or dust and without the necessity for a screen or umbrella to catch the debris, and without damage to expensive rugs or other furniture.

With these and other objects in view, my invention is shown in the accompanying drawings, and will be hereinafter more fully described with reference thereto and finally pointed out in the claim.

In the accompanying drawings:

Figure 1 is a perspective view of my improved invention.

Fig. 2 is an end view thereof.

Fig. 3 is a bottom view thereof.

Fig. 4 shows the same in engagement with the ceiling and before starting the boxing operation.

Fig. 5 shows the auger when half way through the plaster of the ceiling, and

Fig. 6 shows the work completed, and the material cut from the ceiling contained in the auger.

Similar reference characters indicate corresponding parts throughout the several figures of the drawings.

Referring to the drawings, my invention comprises a hollow cylindrical shell or body portion 10 provided at its forward edge with a series of cutting teeth 11, and at its opposite end, a cover plate 12 provided with a central opening is secured thereon by means of screws 13. This plate is preferably provided with several enlarged segmental open-

ings 14 therein to diminish the weight of material. Spaced from the plate 12 there is provided within the cylinder 10 a transverse plate 15 having a central opening 60 therein and secured within the cylinder by means of screws 16. A shaft 17 is mounted in the openings of the plates 12 and 15 which form bearings therefor. The inner end of the shaft is enlarged as at 18, and is provided with an interiorly threaded bore. This enlarged end is normally held in engagement with the plate 12 by means of a spring 19 mounted in the shaft between the under side of the said plate and a collar 20 70 secured on the shaft. The outer end of the shaft is provided with a winged bead 21 to facilitate turning the same.

A handle 22 for turning the cylinder is removably secured to the plate and is bent 75 under the end of the shaft 17. This handle is mounted between guide pieces 23 and 24 formed on the said plate, and is secured in place by means of a screw 25 and washer 26. When not in use the handle may be removed 80 to facilitate carrying.

The operation of my improved auger is as follows:

The position of the opening is determined by the built-in pipe 27, the end of which 85 protrudes slightly outside the plaster 28 and lathing 29, forming the ceiling or wall. The shaft 17 is forced inwardly against the tension of the spring, and the interiorly threaded end thereof is engaged with the protruding end of the pipe 27 by turning of the winged bead 21.

The cylinder it will be seen is now exactly concentric with the pipe 27, and the same is turned by grasping the handle 22. 95 The spring 19 holds the toothed edge of the cylinder in engagement with the ceiling and exerts an inward force thereon. The turning of the cylinder is continued until the lathing is reached, whereupon the cake 100 of plaster will fall into the cylinder together with all dirt and crumbs created during the cutting operation. The opening cut is entirely smooth with no broken corners and the outlet box may be perfectly fitted 105 therein. My improved device may be used in a room without the necessity for removing or covering expensive rugs or other furnishings, and for this reason will prove especially desirable when such work must be 110 done during the occupancy of a building.

I have illustrated and described a pre-

ferred and satisfactory form of my invention but it is obvious that changes may be made therein and that the same may be used for various purposes, all within the spirit and scope thereof as defined in the appended claim.

I claim:

A cutting device for plaster walls adapted to engage a fixture therein and comprising
10 a rod provided with means for engaging said fixture and with a stop, a rotary tubular cutter disposed on said rod and provided

with an interior abutment and at its outer end with a cutting edge, an expansive spring disposed on said rod between said stop and 15 said abutment, and means for turning said tubular cutter.

In testimony, that I claim the foregoing as my invention, I have signed my name in presence of two subscribing witnesses.

JOHN F. ALEXANDER.
